(57) CLAIM

The ornamental design for a light fixture as shown and described.

DESCRIPTION

FIG. 1 is a front, left and top perspective view of a light fixture showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a front, left and top perspective view of another state of the light fixture thereof; and,

FIG. 10 is a rear, right and bottom perspective view of another state of the light fixture thereof.

The broken lines are included for the purposes of illustrating portions of the light fixture that form no part of the claimed design.
